DESIGN FOR A VENETIAN BLIND HEAD-BAR CENTER SUPPORT

Jules Nisenson, New York, N. Y., assignor to
Publix Metal Products, Inc., New York, N. Y.,
a corporation of New York

Application May 23, 1944, Serial No. 113,727

Term of patent 7 years

(Cl. D21—1)

To all whom it may concern:

Be it known that I, Jules Nisenson, a citizen
of the United States of America and a resident
of the Borough of Manhattan, city, county, and
State of New York, have invented a new, original,
and ornamental Design for a Venetian Blind
Head-Bar Center Support, of which the following
is a specification, reference being had to the
accompanying drawing, forming a part thereof.

Figure 1 is a front view in perspective of a

Venetian blind head-bar center support, showing
my new design.

Figure 2 is a rear view in perspective of the
Venetian blind head-bar center support, shown
in Figure 1.

I claim:

The ornamental design for a Venetian blind
head-bar center support, as shown.

JULES NISENSON.
